(57) **ABSTRACT**

The invention relates to an incubator with a thermoregulating arrangement for newborns suffering from pathologies, comprising a closed compartment consisting of a horizontal partition that separates an upper part from a lower part, wherein the upper part has receiving and housing elements for the newborn, while the lower part has respective means and elements for thermoregulation, measurement, etc., which allow the production of air flows that maintain environmental conditions according to the newborn's needs.

**INCUBATOR WITH THERMOREGULATING
ARRANGEMENT FOR NEWBORNS
SUFFERING FROM PATHOLOGIES**

STATE OF THE ART OF THE INVENTION

Field of the Invention

The present invention relates to the field of equipment, means and arrangements employed for newborns, preferably for pathological ones, and more particularly it relates to a non-invasive thermoregulating medical device for a pathological newborn which, unlike conventional incubators, allows the regulation of temperature within the environment in which the pathological newborn is found without the need to use equipment, instruments or external means.

While mention is made of an incubator throughout the present description, it should be understood that it is a novel non-invasive and thermoregulatory sanitary product which can either lower the temperature to the newborn or raise it. This clarification is made because the term incubator associated with popular usage and custom, is understood as a heating or brooding element.

Description of the Prior Art

In order to better understand the object and scope of the present invention it is convenient to describe the current state of the art in reference to pathological newborns and the disadvantages that arise during the preventive care thereof.

Pathological newborns need a range of special care from birth and during their stay in the observation unit or neonatal intensive care unit. This is because they are very likely to have sequelae that are difficult to treat, such as blindness, deafness and cerebral palsy, which in many cases are prevented with adequate follow-up. To do this, parameters such as heart and respiratory rate, temperature, pulse oximetry, blood glucose and serum calcium levels should be controlled in the Monitoring Unit, among other important parameters. However, despite the greater internal efficiency of hospitals in their neonatal intensive care units, there is a lack of external efficiency due to the lack of follow-up networks that involve all levels of health care, either from care Primary level in the first level to reach the centres of high complexity to solve the most serious problems. This situation is responsible for the death of many children at risk.

Currently, one of the devices that are used for the treatment of pathological newborns, hereinafter pathological NB, is the incubator. Such incubator works as an artificial uterus that recreates an optimal environment for the newborn, being a closed space well insulated thanks to the air filters that are in the ducts to the outside. These filters are able to retain dust and allergens present in the environment, but also prevent bacteria or germs from coming into contact with the newborn. On the other hand, in order to control hydration, not only the temperature of the environment is important, but so is the degree of humidity, since a very dry environment favours dehydration even at low temperatures. The incubator has sensors that when they detect a sensible decrease of the relative humidity, they cause that the humidifiers of the environment are activated. In addition, the incubator can present an electronic balance that keeps a continuous record of the NB's weight. Thanks to the provision of the balance, you can keep a record of the evolution of the NB without having to move it to other sectors for their respective analysis.

2

On the other hand, the newborn has on its body surface several electrodes capable of recording the basic vital functions. These sensors include an electrocardiogram that records the heart rate, an electroencephalogram that records brain activity, and respiratory rate sensors. All of them are adapted to both premature and non-premature babies.

In summary, one of the most important reasons the incubator is used is the difficulty of many newborns, especially premature or underweight, to maintain their body temperature at 36-37° C., naturally. The incubator allows them to maintain a suitable temperature until they themselves are able to maintain it without difficulty. In cases where a term NB must be cooled with Ischemic Intrapartum Hypoxia "IH", ice or water at 10° C. are used in contact and conduction bags, which lower the temperature of the NB, thus preventing death or brain damage. Although the use of the incubator has helped to keep NBs in stable environmental conditions, there are still a number of drawbacks to maintaining temperatures suitable for certain pathologies. Likewise, the use of external equipment or means to cool the NB many times makes difficult the work of the specialist who must treat the NB.

In virtue of the current state of the art available for pathological newborns, it will be very convenient to have a new thermoregulating apparatus which is constituted and constructed to solve the aforementioned drawbacks and, in addition, to allow better environmental conditions for newborns without the need to resort to external equipment or resources.

BRIEF DESCRIPTION OF THE INVENTION

It is therefore an object of the present invention to provide a non-invasive, thermoregulating medical product which provides better environmental conditions therein so that pathological newborns can be stable and safe.

It is yet another object of the present invention to provide a thermoregulating means or arrangement within the environment which allows both heating and cooling thereof.

It is still another object of the present invention to provide an incubator which does not use external means to cool pathological NB.

It is yet another object of the present invention to provide at least one hot or cold air circulation flow which envelops the NB within a bubble without the air flow coming into contact with the NB.

It is a further object of the present invention to provide at least two air circulation flow that regulate the proper temperature within the environment and further allow visibility towards the interior of the incubator.

It is another object of the present invention to provide an incubator which, unlike conventional incubators which only heat the environment, allows for cooling of the compartment thanks to the arrangement of a thermoregulating element.

It is yet another object of the present invention to provide an incubator with a thermoregulating arrangement for newborns suffering from pathologies, comprising a closed compartment which externally has a plurality of openings and an access door, while internally it is comprised of a horizontal partition defining an upper part where the newborn is resting and a lower part provided with measuring elements and thermoregulating means that produce air flows, that maintain the newborn at required temperatures, wherein said upper part comprises an outer hood separated from an inner hood, an upper external circulation channel being defined therebetween, said partition is provided with end communication holes which communicate with each other to the
